Attorney

UNITED STATES PATENT OFFICE.

FRANK VANSANT, OF TOPEKA, KANSAS.

WINDOW SASH.

Application filed February 23, 1923. Serial No. 620,773.

To all whom it may concern:

Be it known that I, FRANK VANSANT, a citizen of the United States, residing at Topeka, in the county of Shawnee and State of Kansas, have invented a new and useful Window Sash, of which the following is a specification.

This invention aims to provide novel means whereby a window sash may be held in spaced relation to a window frame, thereby permitting the edges of the sash to be painted, the construction being such that the sash, nevertheless, will have a tight fit in the frame, so that wind or rain cannot find its way about the periphery of the sash.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in elevation, a device constructed in accordance with the invention; Figure 2 is a section on the line 2—2 of Figure 1; Figure 3 is a section on the line 3—3 of Figure 1, with the upper sash lowered; Figure 4 is a section on the line 4—4 of Figure 1; Figure 5 is a section on the line 5—5 of Figure 1; and Figure 6 is a fragmental elevation showing a detail.

The numeral 1 marks a window frame including side rails 2, a lintel 3 and a sill 4. The numeral 5 designates a lower sash including stiles 6, a top rail 7 and a bottom rail 8. The numeral 9 designates an upper sash including stiles 10, a bottom rail 11 and a top rail 12. A metal strip 14 is secured to the stiles 10 and to the top rail 12 of the upper sash 9 and projects beyond the periphery of the sash. A metal strip 15 is secured to the stiles 6 and to the bottom rail 8 of the lower sash 5. The strip 15 projects laterally beyond the stile 6 of the lower sash 5 and terminates approximately flush with, or slightly above, the bottom rail 8 of the lower sash 5, as shown at 16 in Figure 4. In order to effect a weather-tight joint be-

tween the lower sash and the sill, a recess 17 may be formed in the bottom rail 8 of the lower sash 5, behind the lower portion of the strip 15, and in said recess, is held a resilient packing member 18, as clearly shown in Fig. 4.

A grove 19 is formed in the lintel 3 of the window frame 1. A metal trough 20 is located in the groove 19, the trough 20 comprising a flat wall 21 and a reversely curved wall 22 defining an inwardly projecting rib 23. The wall 21 of the trough 20 has a flange 24 secured at 25 to the lintel 3. The wall 22 is provided with a flange 26 in slideable engagement with the lintel 3. The flange 26 is not secured to the lintel 3. When the upper sash 9 is raised, the projecting portion of the upper part of the metal strip 14 enters the trough 20, the part being resilient, and the rib 23 bearing on the projecting portion of the strip 14, to afford a weather tight joint. The side rails 2 of the frame 1 are supplied with grooves 27 wherein troughs 28 are mounted. The troughs 28 are constructed like the trough 20. The projecting portions of the side members of the strip 14 slide in the troughs 28 and afford a weather tight joint. Grooves 29 are formed in the side rails 2 of the window frame 1. The troughs 30 are mounted in the grooves 29. The troughs 30 are constructed like the trough 20. The projecting parts of the side members of the strip 15 are received slidably in the troughs 30, weather tight joints being provided.

The general construction of the device is such that the weather cannot find its way into the building about either of the sashes 5 or 9. The side portions of the strips 15 and 14 serve to space the vertical edges of the sashes 5 and 9 from the side rails 2 of the frame 1 and, consequently, the edges of the sashes and the inner surfaces of the side rails 2 may be painted, and the paint will not be rubbed off, warping or deterioration of the wood work being prevented.

In order to hold the sashes in spaced relation to the side portions of the window frame 1, bowed spring strips 31 are provided, the upper ends of the strips 31 being secured at 32 to the side rails 2. The strip 31 has a flat end 33 bearing slidably on the inner edge of the side rail 2 of the window frame 1, the intermediate portion of the strip bearing against the stile 6 of the lower

sash 5. Similar spring strips may be supplied for holding the upper sash 9 in spaced relation with the side rails 2 of the frame 1.

If desired, a strip 50 may be secured at 5 to the bottom rail 11 of the upper sash, as shown in Figure 5, the strip being adapted to overlap the top rail 7 of the lower sash, and serving to prevent air from finding its way between the rails 7 and 11.

10. What is claimed is:—

In a device of the class described, a frame having a groove, a trough disposed in the groove and comprising walls, one of which is flat, and the other of which is curved to 15 form a rib, the walls having oppositely extended flanges overlapped on the frame,

means for securing the flange of one wall to the frame, the flange of the other wall being slideable on the frame, a sash slideable in the frame, and a strip carried by the sash and projecting beyond the sash, the strip being slideable in the trough and co-operating with the flat wall thereof, the rib engaging the strip.

In testimony that I claim the foregoing 25 as my own, I have hereto affixed my signature in the presence of two witnesses.

FRANK VANSANT.
